UNITED STATES PATENT OFFICE.

JOHN W. HOBBS, OF BOSTON, MASSACHUSETTS, ASSIGNOR TO A. O. NORTON, INC., OF BOSTON, MASSACHUSETTS, A CORPORATION OF MAINE.

LIFTING JACK.

Application filed May 10, 1926 Serial No. 107,846.

This invention relates to lifting jacks and its object is to provide a jack having a plurality of selective speeds operated from the same power shaft and with the same power devices, and without requiring any change of position of the power devices.

A further object of the invention is to provide a jack with a plurality of selective speeds operated from the same power shaft and 10 means for shifting from one speed to the other independent of the power devices and without requiring any change therein.

In the accompanying drawings illustrating a selected embodiment of the invention:

15 Fig. 1 is an elevation of the jack.

Fig. 2 is a top plan view.

Fig. 3 is a sectional elevation on the line 3—3 of Fig. 1.

20 Fig. 4 is a section on the line 4—4 of Fig. 3.

Fig. 5 is a section on the line 5—5 of Fig. 3.

Referring to the drawings 6 is a lifting member arranged within the hollow standard or shell 7 and operated by the screw 8 having a bevel gear 9 rigid with its lower end 25 and mounted on a ball bearing 10 in the bottom of the standard. A horizontal shaft 11 is journaled in bearings 12 in the standard and carries a rigid bevel gear 13 which meshes with the bevel gear 9.

30 A power shaft 14 is journaled in bearings 15 in the standard and it is provided with a socket 16 adapted to receive an operating lever or bar 16'. The socket may be of any kind usually employed in lifting jacks to 35 receive the operating lever or bar and suitable for this purpose, it being generally provided with a pawl and ratchet. But I do not consider it necessary to enter into a detail description of this element of the jack because 40 its particular construction does not form any part of this invention. The socket may be permanently mounted on the power shaft so far as the present invention is concerned because, as will appear herein, there is no necessity for removing the socket or changing its 45 position on the power shaft to shift between high and low speeds.

A part 14' of the power shaft is squared (Fig. 3) and a gear 17 is mounted to slide on this part and is provided with a side extension 17' having a groove 18. A shifter is mounted on the standard for shifting the grooved gear 17 on the power shaft between high speed and low speed positions, and this shifter comprises a vertically disposed shaft

19 (Fig. 4) mounted in the standard and carrying at its lower end an arm 20 which operates in the groove 18, and having a crank handle 21 on its upper end on the outside of the standard. A spring pressed button 22 60 in this handle engages the standard to hold the shifter in adjusted position.

An idler gear 23 (Fig. 4) journaled in the standard is in constant mesh with a high speed gear 24 keyed on the shaft 11. An idler 65 gear 25 is journaled in the standard and is in constant mesh with the low speed gear 26 keyed on the shaft 11. The shifter gear is adapted to be shifted on the squared part of the power shaft to mesh with the high speed 70 idler gear 23 or with the low speed idler gear 25, and this shifting of the shifter gear 17 is easily accomplished by operating the crank handle 21 and without changing the power socket or the power lever in any respect whatever. The gears 17, 23 and 24 provide a high speed chain of gearing which may be made in any desired ratio; the gears 17, 25 and 26 provide a low speed chain of gearing which may be made in any desired ratio. The gears 24 and 26 are keyed on the driven shaft 11 75 between the rigid bevel gear 13 and the bearing 12 of said shaft. The idler gears 23 and 25 are journaled in bearings in the standard, and by this I mean generally the shell or frame 80 of the jack, and including thereby a skeleton frame supporting the speed mechanism and detachably engaged with the standard in or about the manner employed in some jacks at the present time. The shifter gear 90 16 is slideable on the squared part 14' of the power shaft and is shown in a neutral position between the gears 23 and 25 in Fig. 3, the gear 25 not appearing in this section but being disposed opposite the gear 26, as shown 95 in Fig. 4.

My invention is simple in construction, involves but few parts, and is capable of operation easily and without the exercise of special skill. It is highly desirable to provide 100 a jack which is capable of lifting heavy loads as well as light loads and to facilitate the operation of the jack by providing two speeds. It is not broadly new to provide a jack with two speeds but, so far as I am 105 aware, this has only been accomplished by providing a removable operating lever socket and shifting the socket from one shaft to another to change the speed. The present invention avoids the necessity for providing 110

a removable socket, for shifting the socket and for providing two shafts upon which the socket may be removably mounted. Furthermore, the invention is self contained, 5 does not require removal of any parts and the speed can be easily changed by simply operating the shifter crank handle.

The desirability of providing a jack with a change of speed is largely a matter of labor 10 and load, for with a change of speed the jack can be operated by one man to lift a light load at high speed or a heavy load at low speed, and by two men to lift a light load or a heavy load at high speed. 15 The construction may be such that in high speed the screw will travel twice as fast as in low speed, or different ratios may be provided as desired.

Changes in the form, construction and arrangement of parts of the invention may be made without departing from the spirit or sacrificing the advantages thereof and I reserve the right to make all such changes as fall within the scope of the following claims. 20

25 I claim:

1. A lifting jack comprising a standard, a screw revolubly mounted in said standard, a lifting member slidably mounted in said standard and adapted to be translated by 30 said screw, selective high speed and low speed gearing for operating said screw, a power shaft revolubly mounted in said standard, and means slidably mounted on said power shaft for operating said gearing.

35 2. A lifting jack comprising a standard, a screw revolubly mounted in said standard, a lifting member slidably mounted in said standard and adapted to be translated by said screw, means for operating said screw

comprising high speed gearing and low 40 speed gearing, a power shaft revolubly mounted in said standard, means slidably mounted on said power shaft and revoluble therewith for selectively operating said high speed or low speed gearing, and means projecting from the standard and cooperating 45 with the second named means for shifting said second named means into operating position.

3. A lifting jack comprising a standard, 50 a screw revolubly mounted in said standard, a lifting member slidably mounted in said standard and adapted to be translated by said screw, means for operating said screw comprising high speed gearing and low speed 55 gearing, a power shaft revolubly mounted in said standard, a gear slidably mounted on said power shaft and revoluble therewith, a shifter for selectively moving said gear into engagement with either said high or low 60 speed gearing, and means to revolve said power shaft.

4. A lifting jack comprising a standard, a screw revolubly mounted in said standard, 65 a lifting member slidably mounted in said standard and adapted to be translated by said screw, means for operating said screw comprising high speed gearing and low speed gearing, a power shaft revolubly mounted in said standard, a gear slidably mounted 70 on said power shaft and revoluble therewith, a grooved extension on said gear, a shifter crank on said standard, an arm engaging said groove and operated by said crank for selectively moving said gear into engagement 75 with either said high speed or low speed gearing, and means for revolving said power shaft.

JOHN W. HOBBS.
